AIRPORT LIGHTING SYSTEM

Harry N. Newstedt, Chicago, Ill., assignor to Automatic Electric Laboratories, Inc., Chicago, Ill., a corporation of Delaware

Application October 26, 1945, Serial No. 624,776

6 Claims. (Cl. 177—352)

1

The present invention pertains to airport lighting systems and, more particularly, to improved remote control apparatus therefor.

An airport conventionally comprises a flying field having a plurality of airplane runways thereon, some of the runways being arranged in intersecting relationship with respect to other ones of the runways and in non-intersecting relationship with respect to still other ones of the runways. Illuminating devices of some form are usually provided for the purpose of lighting the runways when the flying field is not otherwise clearly visible; and occasionally traffic signals of some form are provided for the purpose of governing airplane traffic on the runways.

It has heretofore been proposed to provide switching arrangements, for selectively controlling the illumination of the runways in an airport lighting system of the type noted, which would positively prevent the control of the illuminating means associated with conflicting runways. Such a system has been disclosed in Patent 2,296,936, issued to Logan et al. on September 29, 1942.

It is an object of the present invention to provide improved switching arrangements, for selectively controlling the illumination of the runways in an airport lighting system, which will positively prevent the control of the illuminating means associated with conflicting runways, and which is simpler in construction and operation than previously proposed systems.

A further object of the invention is to provide a switching apparatus which is responsive to the successive transmission of a series of impulses over a control line to alternately energize and de-energize a corresponding one of the illuminating means associated with the airport.

Still another object of the invention is to provide a switching apparatus which is responsive to a series of impulses transmitted over a control line to energize a corresponding one of the runway illuminating means, and to prevent control of other ones of the illuminating means until said one illuminating means has been de-energized by the subsequent retransmission of the corresponding series of impulses.

A still further object of the invention is to provide a switching apparatus for selectively or simultaneously energizing several different run-

2

way illuminating means which is arranged to prevent selective de-energization of the group of energized runway illuminating means.

A feature of the invention is the provision, in a switching apparatus for selectively energizing different runway illuminating means to a variable degree from a common source, of means responsive to a selection for disabling the source while the selection is completed, whereby smaller and 10 more economical contactors may be employed.

Other objects and features of the invention will appear upon a further perusal of the specification and accompanying drawings, wherein:

Fig. 1 is a schematic diagram of the apparatus 15 which is located in the control tower of the airport;

Fig. 2 is a schematic diagram of the selecting apparatus, located at a central switching point, together with the beacon light and boundary 20 lights controlled thereby;

Fig. 3 shows the selecting relays which control the intensity of the runway lights which are energized;

Fig. 4 shows the selecting relays for controlling 25 the illumination of the runways; and

Fig. 5 shows the runway lights and energizing circuits therefor.

All of these figures should be placed side by side in numerical order to form a unified system.

Described briefly, the system comprises a selector switch of the Strowger type, located at a central switching point, which is controlled by alternating current impulses transmitted over a two wire line from the control tower. This selector switch 30 has access to three groups of selecting relays; one group of which controls miscellaneous lights, such as the beacon and boundary lights; a second group determines which runway, or group of runways, is to be illuminated; and the third group

40 controls the brightness of the energized runway lights. Each lamp, or group of lamps, is assigned a corresponding two digit number. A further number is assigned to a combination of the lamps associated with a pair of non-intersecting runways. The miscellaneous and runway light selecting relays are arranged to alternately energize and de-energize the corresponding lamps in response to the successive selection thereof by the selector switch. The runway light selecting 45 relays are further arranged to prevent a new

selection from being made while any runway lights are energized. Both the light intensity and the runway light selecting relays are arranged to open a common point in the energizing circuits for the runway lights, during the switching operations resulting from a new selection, whereby the contactors involved in these switching operations need not make or break energized circuits.

A second selector switch is located in the control tower and is arranged to be operated concurrently with the selector switch at the switching point under the control of an impulse transmitter, or dial, of the type commonly employed in telephone systems. This second selector switch has access to three groups of selecting relays, which are duplicates of those provided at the central switching point, and which control indicating lamps located before the dispatcher to enable him to observe the operation of the system. Sound powered telephone handsets, employing transmitter and receiver units of the type fully described in Patent 2,241,105, issued May 6, 1941, to A. E. Woodruff et al., are provided in the control tower and at the switching point to permit communication therebetween over the control line.

The switching point is also arranged to permit testing of the switching apparatus thereat, by means of an impulse transmitter, independently of the control tower.

Referring now to Fig. 1, there is shown a sound powered telephone 100, a key 101, an impulse transmitter 102, a two-digit selector switch 103, a telephone ringer 104 and associated alternating current relay 140, and three groups of indicating relays 105, 106, and 107 together with the indicating lamps controlled thereby. Conductors 108 and 109 extend between the control tower and the switching point.

In Fig. 2 there is shown a sound powered telephone 200, a key 201, an impulse transmitter 202, a two-digit selector 203, a telephone ringer 204 and associated relay 240, an alarm relay 245 and associated alarm lamp 249, miscellaneous light control relays 250, 255, 260 and 265, and contactors 270 and 275 which control the circuits to the beacon light 272 and the boundary lights 277, respectively, the latter being energized through a constant current transformer 278. The miscellaneous light control relays are connected to the bank contacts of selector switch 203 over cable 205. The light intensity control relays (Fig. 3) and runway light control relays (Fig. 4) are similarly connected to the bank contacts of selector switch 203 over cables 305 and 405, respectively. The last two groups of relays control contactors 510 to 530 and 540 to 560, respectively. Contactors 510 to 530 control the primary to secondary turns ratio of current transformer 570 and thus control the brilliance of runway lamps R1 to R3 which are not short-circuited by contactors 540 to 560. Transformer 570 is energized by the constant current transformer 580 from a source of high voltage alternating current through contacts of contactor 560.

It will be noted that when the miscellaneous light control relays are restored the contactors 270 and 275 are operated to energize the beacon light 272 and the boundary lights 277. The corresponding indicating lamps 272' and 277', respectively, shown in Fig. 1 will also be energized. In order to extinguish the beacon light the dispatcher operates key 101 to the right and then dials the two digit number assigned to the beacon

light. When key 101 is operated to the right it completes a circuit to relay 120 in series with the impulse transmitter 102. Relay 120 operates, closes a circuit to relay 125 at contacts 122, and completes a circuit to relay 220 at contacts 121. The latter circuit may be traced from one side of the 110 v. A. C. supply through contacts 121, contacts of key 101, contacts 141, over conductor 109, through contacts of key 201, full wave rectifier 209 and relay 220, contacts 246, contacts of key 201, over conductor 108, and through contacts of key 101 to the other side of the 110 v. A. C. supply. Relay 220 operates and closes a circuit to relay 225 at contacts 221. Relays 125 and 225 operate.

15 The dispatcher now dials the number assigned to the beacon light, which number will be assumed to be 41. When the impulse transmitter 102 is operated to transmit the first digit, the circuit to relay 120 is momentarily interrupted four times in succession. Each time that relay 120 restores it opens the circuit to relay 220 at contacts 121 and closes a circuit to the vertical magnet 105 of the selector switch in series with relay 130. The latter circuit is completed from ground through contacts 122, 126, and normally closed contacts of the vertical off-normal springs 106, initially, and through make contacts of the vertical off-normal springs 106 and contacts 131 after relay 130 has operated and the vertical off-normal springs have been operated in response to the operation of the switch shaft to the first level by the vertical magnet 105. Relay 220 is momentarily restored four times in succession concurrently with relay 120 causing the vertical magnet 35 205 to step the switch shaft of selector switch 203 to the fourth level. The circuits of the selector switch 203 need not be traced since they are identical to those traced for selector switch 103. Relays 125, 130, 225 and 230 are rendered slow to 40 release by copper sleeves placed over their cores so that they remain operated during impulsing. Shortly after the series of impulses have been transmitted by the impulse transmitter 102, relays 130 and 230 restore to transfer the impulsive circuits of the selector switches from the vertical magnets 105 and 205 to the rotary magnets 110 and 210, respectively.

45 When impulse transmitter 102 is again operated to transmit the second digit relays 120 and 220 will each be momentarily released once. When relay 120 restores it completes a circuit from ground through contacts 122, 126, make contacts of the vertical off-normal springs 106, contacts 131, and through relay 135 and rotary magnets 110 to battery. Relay 220 completes a similar circuit to rotary magnets 210 in series with relay 235. Relays 135 and 235 operate and open points in the circuits to wipers 137 and 237, respectively. Rotary magnets 110 and 210 operate to rotate the 50 wipers 137 and 237, respectively, to the first bank contacts of the fourth level. Relays 135 and 235 restore shortly after relays 120 and 220 have re-operated. When relay 235 restores it completes a circuit from ground through contacts 221 and 55 236 to wiper 237, thence to the first contact on the fourth level and over conductor C41 to cable 205 to the lower winding of relay 255. Relay 255 operates, opens the circuit to contactor 270 at contacts 256, and closes a holding circuit to its lower winding in series with the lower winding of relay 250 at contacts 258. Contact 270 restores and disconnects the 2300 v. A. C. supply from beacon light 272 at contacts 271. In a similar manner, ground is extended through wiper 137 60 and the first bank contact on the fourth level of

selector switch 103 and over conductor C41' to operate a relay corresponding to relay 255 and thereby extinguish the indicating lamp 272'.

Key 101 is now restored causing relays 120 and 220 to restore and remove grounds from wiper 137 and relay 125 at contacts 122 and from wiper 237 and relay 225 at contacts 221. When ground is removed from conductor C41 a short-circuit is removed from the lower winding of relay 250 causing it to be energized in series with the lower winding of relay 255. Relay 250 operates and transfers conductor C41 to the upper windings of relays 250 and 255 in multiple at contacts 251. A similar operation takes place in the miscellaneous light indicating relay group 105. When relays 120 and 220 restored they also reclosed the circuits to rotary magnets 110 and 210 causing wipers 137 and 237 to rotate to the next contact but without effect. Relays 125 and 225 subsequently restore and complete obvious circuits to the selector switch release magnets 138 and 238 at contacts 126 and 236, respectively. The circuits to the rotary magnets are also opened at the latter contacts. The release magnets operate to permit the selector switch shafts to restore to normal when the vertical off-normal springs restore to open the release magnet circuits.

The boundary lights may be extinguished in the same manner by dialing the number 31 assigned thereto. In this case wipers 137 and 237 will be stepped to the first contact in the third level to ground conductors C31 and C31'. Relay 265 will then be operated to release contactor 275, and a corresponding relay in the miscellaneous light indicating relay group 105 will be operated to extinguish indicating lamp 277'.

The beacon lights may be re-energized by again dialing 41. When conductor C41 is grounded the second time a circuit is completed from ground over conductor C41 through contacts 251 directly to the upper winding of relay 250, and through contacts 257 to the upper winding of relay 255. The latter relay is differentially wound and therefore restores when both of its windings are energized, closes the circuit to contactor 270 at contacts 256, opens the circuit to its upper winding at contacts 257, and opens the circuit to its lower winding in series with the lower winding of relay 255 at contacts 258. Contactor 270 reoperates to close the circuit to beacon light 272 at contacts 271. Relay 250 is held by its upper winding until ground is removed from conductor C41 by the restoration of relay 220. The second grounding of conductor C41' causes corresponding operations to take place in the miscellaneous light indicating relay group 105 to re-energize lamp 272'.

For the sake of simplicity only three groups of runway lights have been shown. The system is arranged to permit selective energization of any one of these three groups, or simultaneous energization of groups two and three. All three groups of lamps are connected in series and each group is normally short-circuited by contacts of a corresponding one of the contactors 540 to 550. Any one of these contactors may be operated by the dispatcher by dialing the corresponding numbers 21 to 23, or contactors 550 and 560 may be operated simultaneously by dialing 20, in a manner to be described presently. Operation of these contactors will have no effect until the light intensity control relays are operated by dialing 51, 52 or 53, unless these relays have previously been operated.

If it is desired to cause the first group of runway lights R1 to be energized at a low value of current, either the corresponding runway light number 21 or the corresponding intensity number 51 may be dialed first. It will be assumed that 21 is dialed first and that no previous selection has been made. The dispatcher first operates key 101 to the right and then proceeds to dial 21 by means of the impulse transmitter 102 to step the selector switches 103 and 203 to the first contact of the second level in the same manner as previously described. Selector 203 then extends ground over conductor C21 of cable 405, through contacts 414, 419 and 472 to relay 490. Relay 490 operates; closes a circuit from one side of the 110 v. A. C. supply over conductor 570, through contacts 491, over conductor 542, and through contactor 540 to the other side of the 110 v. A. C. supply; and closes a holding circuit to itself through the upper winding of relay 470 and contacts 432 at contacts 492. When ground is removed from conductor C21 in response to the restoration of key 101 a short circuit is removed from the upper winding of relay 470, thus causing it to be energized in series with relay 490. Relay 470 operates and closes a circuit to relay 410 at contacts 474. Relay 410 operates, closes a circuit to the lower winding of relay 415 from ground through contacts 493 at contacts 411, and opens points in the operating circuits to relays 480 and 485 at contacts 412 and 413, respectively. Relay 415 operates and extends conductor C21 through contacts 471 and 418 to relay 420. No further operations will take place in the runway light control relay group unless the number 21 is again dialed. Corresponding operations take place in the runway light indicating relay group under the control of selector switch 103 to cause lamp 540' to be energized.

The dispatcher now reoperates key 101 and dials 51 to cause selector switches 103 and 203 to step to the first contact on the fifth level and ground conductors C51' and C51, respectively. The ground extended over conductor C51 energizes relay 380 through contacts 314 and 371. Relay 380 operates; closes a circuit from one side of the 110 v. A. C. supply over conductor 571 of cable 505, through contacts 381, over conductor 512 of cable 505, and through contactor 510 to the other side of the 110 v. A. C. supply; closes a holding circuit to itself through the lower winding of relay 319 and contacts 329 at contacts 382; and closes a circuit from ground through contacts 321, 333 and 326, over conductor 447, and through contacts 421, 494 and 443 to relay 445. Relay 445 operates and closes a circuit to the lower winding of relay 440 at contacts 446. Relay 440 operates after a brief delay due to the slugging effect of its short circuited upper winding, removes the short circuit from its upper winding at contacts 442, and opens the circuit to relay 445 and closes a locking circuit to itself at contacts 443. Relay 445 is rendered slow to release by a copper sleeve placed over its core. During the release time of relay 445, contactor 510 operates over the above traced circuit and connects winding 570a of transformer 570 across the secondary winding of transformer 580 at contacts 511. Relay 445 subsequently restores and closes a circuit to relay 435 through contacts 441 at contacts 446. Relay 435 operates and closes a circuit from one side of the 110 v. A. C. supply over conductor 570, through contacts 436, over conductor 502, and through contactor 500 to the other side of the

110 v. A. C. supply. Contactor 500 operates and closes a circuit to the primary winding of transformer 580 from the 2300 v. A. C. supply at contacts 501. When the primary winding of transformer 580 is thus energized it produces a constant current in its secondary winding, which current flows through winding 570a of transformer 510. The current induced in windings 570b, c and d will be equal to that flowing in winding 570a divided by the ratio between the total number of turns in windings 570b, c and d and the number of turns in winding 570a, since the primary and secondary ampere-turns of a transformer are practically equal. The lights associated with the first runway are thus energized at a low value of current flowing through windings 570b, c and d of transformer 570 and contacts 551, 561 and 511. The light intensity indicating relay group responds to the ground extended over conductor C51' by selector switch 103 to energize lamp 510' in the same manner as light intensity control relays of Fig. 3 energized contactor 510.

The dispatcher restores key 101 to release the selector switches 103 and 203 as previously described. When selector switch 203 removes ground from conductor C51 a short circuit is removed from the lower winding of relay 370 causing it to be energized in series with relay 380. Relay 370 operates and closes a circuit to relay 310 from ground through contacts 384 at contacts 373. Relay 310 operates, locks to ground through contacts 328 at contacts 311, and opens points in the operating circuits to relays 340, 360 and 380 and transfers conductors C53, C52 and C51 to relay 320 through contacts 327 at contacts 312, 313 and 314.

If the dispatcher wishes to increase the current flowing through the energized runway lights to a high value, he may do so by re-operating key 101 and then dialing 53 to cause conductor C53 to be grounded by selector switch 203. The ground extended over conductor C53 energizes relay 320 through contacts 312 and 327. Relay 320 operates and opens the circuit to relay 440 and closes a circuit to relay 315 at contacts 321. Relay 315 is a weighted spring relay of the type disclosed in Patent 1,641,256, issued September 6, 1927, to John Erickson. When this relay operates its weighted spring vibrates for several seconds, preventing immediate operation of relay 325. During this delay interval relay 440 restores and opens the circuit to relay 435 at contacts 441. Relay 435 restores and opens the circuit to contactor 500 at contacts 436. Contactor 500 restores and disconnects the 2300 v. A. C. supply from transformer 580 at contacts 501. As the amplitude of vibration of the weighted spring of relay 315 decreases, the average current flowing in relay 325 gradually increases until it is able to operate. When relay 325 operates it opens the circuit to relay 320 at contacts 327 and opens the holding circuit to relay 380 at contact 329. Relay 380 restores, opens the circuit to contactor 510 at contacts 381, and opens the operating circuit to relay 310 at contacts 384. Relay 370 remains operated due to the energization of its upper winding from ground over conductor C53 and through contacts 312, 314 and 372. Contactor 510 restores. Relay 320 restores after a brief delay, opens the circuit to relay 315 at contacts 321, and opens the locking circuit to relay 310 at contacts 322. Relay 310 restores, opens the holding circuit to the upper winding of relay 370 at contacts 314, and ex-

5 tends the ground on conductor C53 to relay 340 through contacts 331 at contacts 312. Relay 370 restores. Relay 340 operates, closes a circuit to contactor 530 over conductors 532 and 571 at contacts 341, and closes a holding circuit to itself through the lower winding of relay 330 and contacts 322 at contacts 342. Relay 325 restores and closes a previously traced circuit to relay 445 over conductor 447 at contacts 326. Relays 445 and 440 operate, relay 445 restores and relay 435 operates as previously described to close a circuit to contactor 500 over conductors 502 and 570 at contacts 436 after a predetermined time interval. During this interval contactor 530 will have operated to connect windings 570a, b and c of transformer 570 across the secondary of transformer 580 at contacts 531. Contactor 500 subsequently operates to reclose the 2300 v. A. C. supply circuit to the primary of transformer 580 at contacts 501. The current now flowing through the energized runway lights will be equal to the constant current output of transformer 580 multiplied by the ratio between the total number of turns in windings 570a, b and c to the number of turns in winding 570d. A high value of current is thus produced in the circuit including winding 570d, runway lights R1, and contacts 551, 561 and 531. The operations which take place in the light intensity control relay group in response to the grounding of conductor C53 are duplicated in the light intensity indicating relay group 106 in response to the grounding of conductor C53' by selector switch 103. Lamp 510' is thus extinguished and lamp 530' is energized.

When the dispatcher restores key 101 the selector switches 103 and 203 release, thereby removing grounds from conductors C53' and C53, respectively. The removal of ground from conductor C53 removes a short circuit from the lower winding of relay 330 causing it to be energized in series with relay 340. Relay 330 operates and closes a circuit to relay 310 from ground through contacts 344 at contacts 333. Relay 310 operates, locks to ground through contacts 328 at contacts 311, and extends conductors C51 to C53 to relay 320 through contacts 327 at contacts 312 to 314.

It will next be assumed that the dispatcher wishes to illuminate runway Number 3. As previously noted, no runway may be illuminated while another is illuminated. Thus if the dispatcher proceeded to operate key 101 to the right and then dialed the number 23 corresponding to runway lights R3, conductor C23 would be 55 grounded by selector switch 203 but without effect since the circuit between this conductor and relay 420 is open at contacts 412. Therefore the dispatcher first dials the number 21 to extinguish runway lights R1. When conductor C21 is 60 grounded by selector switch 203 in response to the dialing of the number 21, circuits are completed from ground over conductor C21, through contacts 471 and 473 to the lower winding of relay 470, through contacts 471, 419 and 416 to the 65 upper winding of relay 415, and through contacts 471 and 419 to relay 420. Relay 420 operates, opens the circuit to relay 440 at contacts 421, closes a circuit to relay 425 at contacts 422, and locks to ground through contacts 431 at contacts 70 423. Weighted spring relay 425 operates and closes an intermittent circuit to relay 430 at contacts 426. Relays 440 and 435 and contactor 500 restore as previously described to de-energize transformer 580. Relay 430 subsequently operates, opens the locking circuit to relay 420 at

contacts 431, and opens the holding circuit to relay 490 through the upper winding of relay 470 at contacts 432. Relay 490 restores, opens the circuit to contactor 540 at contacts 491, and opens the circuit to the lower winding of relay 415 at contacts 493. Contactor 540 restores and short-circuits runway lights R1 at contacts 541. When selector switches 103 and 203 are released by the restoration of key 101, ground is removed from conductor C21 thereby opening circuits to relay 420, the upper winding of relay 415, and the lower winding of relay 470. Relay 415 restores. Relay 470 restores and opens the circuit to relay 410 at contacts 474. Relay 420 restores and opens the circuit to relay 425 which restores and opens the circuit to relay 430. Relay 410 restores and transfers conductors C21 to C23 to relays 490, 485 and 480 at contacts 414 to 412, respectively. Relay 430 restores.

When the dispatcher reoperates key 101 and dials 23 selector switch 203 grounds conductor C23 thereby completing a circuit to relay 480 through contacts 487, 412, 417 and 452. Relay 480 operates, closes a circuit to contactor 560 over conductors 562 and 573 at contacts 481, closes a holding circuit to itself through the upper winding of relay 450 and contacts 432 at contacts 482, and closes a circuit to relay 445 from ground over conductor 447 at contacts 484. Relays 445 and 440 operate, relay 435 restores, and relay 435 operates to close a circuit to contactor 500 over conductors 502 and 579 at contacts 436 after a predetermined time interval, as previously described. During this time interval contactor 560 operates to remove a short circuit from runway lights R3 at contacts 551. Contactor 560 subsequently operates to energize transformer 580 from the 2,300 v. A. C. supply to illuminate the runway lights R3. When selector switch 203 is released by the restoration of key 101, ground is removed from conductor C23 resulting in the energization of the upper winding of relay 450 in series with relay 490. Relay 450 operates, closes a circuit to relay 410 at contacts 454, and opens a point in the operating circuit to relay 405 at contacts 455. Relay 410 operates and closes a circuit to the lower winding of relay 415 from ground through contacts 483 at contacts 411. Relay 415 operates and extends conductor C23 through contacts 497, 451 and 417 to relay 420.

The system is arranged to permit concurrent illumination of runway lights R2 and R3 since the second and third runways are non-interfering. To energize runway lights R2 and R3 simultaneously the dispatcher first dials the number corresponding to the runway lights which are energized, in this case number 23, in order to extinguish them in the previously described manner, and then dials the number 20 corresponding to the combination of runway lights R2 and R3. The runway light control relays will have been restored to normal when the previously energized runway lights were extinguished so that when conductor C20 is grounded by selector switch 203 in response to the dialing of number 20 a circuit is completed through contacts 465 and 455 to the lower winding of relay 405. Relay 405 operates, shunts contacts 455 and 465 at contacts 409, extends conductor C20 to relay 480 through contacts 409, 407, 412, 417 and 452, and extends conductor C20 to relay 485 through contacts 409, 408, 413, 418 and 462. Relays 480 and 485 operate, close multiple circuits to the upper winding of relay 405 through contacts 409 at contacts 483 and 488, and close multiple circuits to relay

445 from ground over conductor 447 at contacts 484 and 489. Relay 480 also closes a circuit to contactor 560 over conductors 562 and 570 at contacts 481, and closes a holding circuit to itself through the upper winding of relay 450 and contacts 432 at contacts 482. Relay 485 also closes a circuit to contactor 550 over conductors 552 and 579 at contacts 486, and closes a holding circuit to itself through the upper winding of relay 460 and contacts 432 at contacts 487. Relays 445, 440 and 435 operate as previously described to close the circuit to contactor 500 over conductors 502 and 578 at contacts 438 after a predetermined time interval during which contactors 560 and 560 operate to remove short circuits from runway lights R2 and R3 at contacts 551 and 561, respectively. When transformer 580 is energized in response to the operation of contactor 500, runway lights R2 and R3 are energized in series with each other and contacts 541 and 531 and winding 570d of transformer 570. When ground is removed from conductor C20 in response to the restoration of key 101 a short circuit is removed from the upper windings of relays 450 and 460 causing them to be energized in series with relays 489 and 485 in multiple with the lower winding of relay 405. Relays 450 and 460 operate, open circuits to the lower winding of relay 405 at contacts 462 and 462, and close multiple circuits to relay 410 at contacts 454 and 454. Relay 410 operates, closes a circuit to the lower winding of relay 415 at contacts 411 from ground through contacts 483 and 488 in multiple, and opens a point in the circuit to relay 490 at contacts 414. Relay 415 operates and extends multiple circuits from conductor C20 to relay 420 through contacts 409, 407 and 408, 451 and 461, and 417 and 418.

If the dispatcher wishes to extinguish one of the two energized groups of runway lights, he must first dial 20 to extinguish both groups of lights and must then dial the number corresponding to the group which it is desired shall remain energized. Selector switch 203 grounds conductor C20, in response to the dialing of the number 20, thereby closing holding circuits to the lower winding of relay 405 through contacts 409, to the lower windings of relays 450 and 460 through contacts 409, 407, 451 and 453 and 409, 408, 461 and 463, and to the upper winding of relay 415 through contacts 409, 407 and 408, 451 and 461, 417 and 418, and 416. Relay 420 is energized in multiple with the upper winding of relay 415. When relay 420 operates it opens the circuit to relay 440 at contacts 421, closes a circuit to relay 425 at contacts 422, and locks to ground through contacts 431 at contacts 423. Weighted spring relay 425 operates and closes an intermittent circuit to relay 430 at contacts 426. Relays 440 and 435 restore to release contactor 500 and thereby de-energize transformer 580. Relay 430 subsequently operates, opens the locking circuit to relay 420 at contacts 431, and opens the holding circuits to relays 480 and 485 through the upper windings of relays 450 and 460 at contacts 432. Relays 480 and 485 restore, open the circuits to contactors 560 and 550 at contacts 481 and 486, respectively, and open the circuits to the upper winding of relay 405 and the lower winding of relay 415 at contacts 483 and 488. Contactors 450 and 460 restore. When selector 203 is released by the restoration of key 101 ground is removed from conductor C20 thereby releasing relays 415, 420, 450 and 460. Relays 450 and 460 restore and open multiple circuits to

11

relay 410 at contacts 454 and 464. Relays 410 and 415 restore. Relay 429 restores and opens the circuit to relay 425 which restores and opens the circuit to relay 430 at contacts 426. Relay 430 restores after a brief delay. The operation of the runway light control relays in response to the dialing of the number corresponding to the runway lights which it is desired shall remain energized should be apparent from the preceding description.

It should be apparent that additional pairs of relays, such as 470 and 490, may be added to control additional runway lights; and that, if there are more than two non-interfering runways, additional relays, such as 495, may be provided to permit simultaneous control of the runway lights in different combinations.

In order to test the operation of the apparatus located at the switching station, the key 201 and impulse transmitter 202 are provided thereat. By operating key 201 to the right the circuit to relay 220 is transferred from conductors 108 and 109 to the 110 v. A. C. supply through the impulse transmitter 202. Selector 203 may then be controlled by the impulse transmitter 202 independently of the control station. If the test man at the switching station wishes to converse with the dispatcher, key 291 is momentarily operated to the left thereby completing a circuit from the 110 v. A. C. source over conductors 108 and 109 in series with condenser 110 and contacts of key 101. Relay 140 operated momentarily, connects the 110 v. A. C. supply at the control station to the ringer 104 at contacts 142, and opens a point in the circuit to the handset 100 and locks to conductor 109 independently of the talk key 101 at contacts 141. The dispatcher responds by operating key 101 to the left thereby connecting the handset 100 through contacts of key 101, contacts 141, over conductors 108 and 109, through contacts of key 201, and through contacts 241 and 221 to the handset 200 for two way conversation. Each handset is equipped with a non-locking switch which must be operated to complete a circuit to the transmitter and receiver therein.

In the event of a failure of the direct current power supply (not shown) used to operate the relays at the switching station, relay 245 will be de-energized. Relay 245 restores, transfers conductor 108 from rectifier 209 to one side of the 110 v. A. C. supply at contacts 246, connects conductor 109 to the other side of the 110 v. A. C. supply at contacts 247, and connects alarm lamp 249 across the 110 v. A. C. supply at contacts 248. The connection of the 110 v. A. C. supply to conductors 108 and 109 causes relay 140 to operate and continuously energize ringer 104 at the control station from the 110 v. A. C. supply thereat to notify the dispatcher of the failure.

The dispatcher may signal the test man at the switching station by operating key 101 to the right and dialing the number 01. Selector switch 203 operates in the previously described manner to extend ground through wiper 237 and the first contact on the tenth level to relay 240. Relay 240 operates, opens a point in the circuit to handset 200 at contacts 241, and connects the 110 v. A. C. supply to ringer 204 at contacts 242. Contacts 241 prevent the application of the 110 v. A. C. signaling current to the transmitter and receiver of handset 200 in the event that the test man operates the handset switch to answer before the circuit to relay 220 is interrupted in response to the restoration of key 75.

12

101. Shortly after dialing 01 the dispatcher operates key 101 from the right to the left, thereby interrupting the operating circuit to relay 220 which restores to release the selector switch 203 and relay 240. When relays 240 and 225 restore the previously traced communicating circuit between handsets 100 and 200 is completed.

What is claimed is:

- 10 1. An airport comprising a flying field having a plurality of airplane runways thereon, illuminating means individually associated with said runways, a control circuit corresponding to each of said runways for controlling the illuminating means individually associated therewith, a selector switch having access to said control circuits, an electric supply circuit for energizing said illuminating means, means common to said control circuits operated in response to selection thereof for automatically rendering said electric supply circuit inactive, said means automatically operated to activate said electric supply circuit after a predetermined time interval.
- 20 2. An airport comprising a flying field having a plurality of airplane runways thereon, illuminating means individually associated with said runways, an electric supply circuit for energizing said illuminating means, a plurality of circuits for changing the intensity of said illuminating means, a control circuit individual to each of said intensity changing circuits and to each of said illuminating means, a selector switch having access to each of said control circuits, means operated in response to the selection of any of said control circuits by said selector switch for automatically rendering said electric supply circuit inactive, said means automatically operated after a predetermined time to activate said electric supply circuit.
- 30 3. In an airport lighting system for an airport having a plurality of runways, a group of lamps individually associated with each of said runways, a control circuit for each of said groups, each control circuit including a control relay, an auxiliary relay, and a control lead, means operated to select any one of said control leads and to apply a control potential thereto, a circuit completed responsive to the selection and application of said potential to said selected control lead for operating said control relay associated therewith, switching means operated in response to the operation of said control relay for illuminating a corresponding group of said lamps, means for removing the control potential from said selected control lead in response to the release of said first means, an auxiliary relay in said selected control circuit operated in response to the removal of said control potential, a relay common to said control circuits operated in response to the operation of any one of said auxiliary relays to disable all of said control circuits except said selected control circuit, thereby, to prevent the operation of other of said control relays, means responsive to the reapplication of said control potential to said selected control lead for releasing said operated control relay, thereby, to control said switching means to extinguish said illuminated group of lamps.
- 40 4. In an airport lighting system as claimed in claim 3 including circuit means for releasing said operated auxiliary relay and said common relay in response to the removal of the reapplied control potential from said selected control lead by the subsequent release of said first means, the releasing of said common relay
- 50
- 60
- 70
- 80
- 90
- 100

conditioning each one of said control circuits for subsequent individual operation.

5. In an airport lighting system having a group of lamps for marking a runway, means for illuminating said lamps, a selector switch, a plurality of intensity control circuits, each having a control lead individually accessible to said selector switch, each one of said control circuits operable individually in response to the selection of the corresponding control lead by said switch to determine a different degree of brilliance for said lamps, and any operated one of said control circuits remaining effective to determine the degree of brilliance until a subsequent selection of any one of said control leads by said switch, a relay common to said control circuits, circuits for operating said relay in response to the release of said selector switch, circuit releasing means, contacts on said relay operated to disconnect all of said control leads from their corresponding control circuits and for connecting all of said control leads to said circuit releasing means, said circuit releasing means operated in response to the subsequent selection of a different one of said control leads by said switch to release any operated one of said control circuits, said common relay released in response to the releasing of said operated control circuit to reconnect each one of said control leads to its corresponding control circuit, and said control circuit corresponding to the last selected one of said control leads operated to determine a different degree of brilliance for said illuminated lamps.

6. In an airport lighting system for illuminating a plurality of runways, a group of lamps for each of said runways, a selector switch, a control circuit for each of said groups, each con-

trol circuit connected to an individual control lead accessible to said selector switch, means to operate said selector switch to select any one of said control circuits, any selected one of said control circuits operated individually in response to its selection to illuminate a corresponding group of said lamps, relay means having a common control lead accessible to said selector switch, said relay means operated in response to the selection of said common control lead to disconnect a plurality of said individual control leads that correspond to non-conflicting runways from their control circuits and to connect said common control lead to said disconnected control circuits, said disconnected control circuits operated in response to their connection to said selected common control lead to illuminate the corresponding groups of lamps concurrently.
